UNITED STATES PATENT OFFICE.

EDWARD L. BURTON, OF SANDWICH, ILLINOIS.

PNEUMATIC HAMMER.

Application filed November 16, 1923. Serial No. 675,145.

My invention relates to improvements in pneumatic hammers, and has for its chief object to provide means for positively holding the rivet-set in the hammer or gun and absolutely prevent its accidental release therefrom, and thereby avoid the damage and injury resulting from such release which frequently occurs with the use of the ordinary rivet-set holder.

10 Other objects will appear hereinafter.

The invention consists in the combinations and arrangements of parts hereinafter described and claimed.

The invention will be best understood by reference to the accompanying drawings forming a part of this specification, and in which—

Fig. 1 is a view of a pneumatic hammer or gun with my invention applied thereto;

20 Fig. 2 is a longitudinal sectional view on line 2—2 of Fig. 1;

Fig. 3 is a cross sectional view on line 3—3 of Fig. 2;

Fig. 4 is a side view of the set holder or holding member for the rivet-set;

Fig. 5 is a side view of the locking sleeve applied over said holder;

Fig. 6 is a view of the pneumatic hammer with a modified form of my invention applied thereto;

Fig. 7 is a longitudinal sectional view on line 7—7 of Fig. 6;

Fig. 8 is a cross sectional view on line 8—8 of Fig. 7;

35 Fig. 9 is a side view of the hinged set holder or holding member of this form of my invention.

In Figs. 1 to 5 of the drawings I have shown the preferred form of construction embodying my invention, and applied to a known type of pneumatic hammer or gun 14 which is provided as usual with a reciprocating rivet-set 15 and a driving member 16 for intermittently striking and actuating said rivet-set.

This preferred form of my invention comprises a holder consisting of a plurality of similar separable parts 17 and 17' extending longitudinally of the hammer, said parts being preferably connected together swingably and hingedly, as by means of interengaging lugs 18 and 18' on said parts and a pin 19 extending through said lugs. An annular flange 20 is provided on the inside 55 of the holder for engaging in the peripheral groove 21 usually provided on the hammer,

said flange being made sufficiently broad and strong to insure positive holding in the groove and to prevent breakage thereof. The lower part of said holder is tapered and made slightly thicker or re-enforced as shown to fit over the lower tapered portion of the hammer, and is provided with an inwardly turned flange 22 which surrounds the rivet-set and is adapted to engage beneath the lateral extending means or annular ridge 23 on the rivet-set, sufficient space or play being provided for the required reciprocation of the ridge 23 between said flange 22 and the end of the hammer.

70 Locking means is provided for positively retaining the rivet-set in operative position, said means comprising a sleeve 24 having a lower tapered portion to embrace and closely fit over the tapered part of the holder, and threads 25 are provided on the interior of said sleeve for engaging co-operating peripheral threads 25' provided on the holder, to fasten said sleeve thereon for positively retaining the holder in position. Additional means is preferably also provided for preventing said sleeve from turning and working itself loose from the holder during the operation of the hammer, said means preferably consisting of a slot 26 in the sleeve, one or more notches 27 provided around the holder, and a catch or spring latch 28 provided with a hook 29 engaging through said slot 26 and into said notch 27, as best shown in Fig. 3, said catch or latch having a tip 30 engageable by a finger for withdrawing the same.

75 The modified form of construction, illustrated in Figs. 6 to 9, inclusive, is shown mounted on a pneumatic hammer or gun 34 having a reciprocating rivet-set 35 and driving member 36 therefor, this construction differing slightly from the preceding form, as shown.

80 In this form of my invention, as in the preceding form, the holder comprises several similar parts 37 and 37' extending longitudinally of the hammer, said parts being preferably swingably and hingedly connected, as by means of lugs 38 and 38' on said parts, and a pin 39 extending therethrough. A strong, inwardly turned annular flange 40 is provided at the upper end of the holder for engaging in the peripheral groove 41 of the hammer, and the holder is also provided 85 with an inwardly turned flange 42 embracing the rivet-set and being adapted to en-

gage beneath the annular ridge 43 provided on the set, sufficient space being provided for reciprocation of the ridge 43 between said flange 42 and the lower end of the hammer.

- 5 The locking means for positively retaining the holder on the hammer and thereby retaining the rivet-set in operative position, comprises a sleeve 44 having an upper contracted portion 44' engaging around the hammer, and said sleeve contains interior threads 45 for engaging co-operating exterior threads 45' tapering upwardly, on the holder to fasten said sleeve thereon and to lock said holder for retaining the rivet-set in its operative position.

10 In the first form illustrated, the sleeve 24 is applied over the lower tapered end of the hammer and after the holder parts have been placed in position on the hammer and over the rivet-set, and the spring catch 28 is snapped in through the slot 26 and into the notch 27; while in the latter form, the sleeve 44 is first placed on the hammer, then 15 the holder parts are applied over the rivet-set and in the groove on the hammer whereupon the sleeve 44 is threaded downward over the holder parts to lock them in position and thereby retain the rivet-set in its 20 operative position and positively prevent release or withdrawal of the set.

25 While I have illustrated and described the preferred form of construction for carrying my invention into effect, this is capable of variation and modification without departing from the spirit of the invention. I, therefore, do not wish to be limited to the precise details of construction set forth but desire to avail myself of such variations and 30 modifications as come within the scope of the appended claims.

35 Having described my invention, what I claim as new and desire to secure by Letters Patent is:

- 40 1. In a pneumatic hammer including a cylinder provided with an annular groove and a rivet-set with a laterally extending portion, a set holder comprising members hinged together and having means engaging 45 in said groove and means engaging beneath said lateral portion, and a locking sleeve embracing and threaded on the upper part of said holder to positively retain the rivet-set in said hammer.

- 45 2. In a pneumatic hammer including a

cylinder provided with an annular groove and a rivet-set with an annular ridge, a set holder comprising a pair of similar members hinged together and having inwardly extending means engaging in said groove and engaging beneath said ridge, and a threaded sleeve surrounding and engaging exterior threads on the upper part of said holder members.

3. In a pneumatic hammer including a cylinder provided with a removable rivet-set, a set holder comprising similar separable members tapered at the lower end, means on said holder for engaging in said cylinder and for retaining said rivet-set, and a sleeve with a tapered portion closely embracing said tapered end and having a threaded portion for drawing said tapered end with increasing firmness over said holder for locking the holder in position.

4. In a pneumatic hammer including a cylinder provided with a groove and a rivet-set, a set holder comprising similar separable members tapered at the lower end, means on said holder for engaging in said groove and for engaging around said rivet-set, means embracing said tapered ends and being threaded over said holder, and latch means on said embracing means engaging in said holder for locking said embracing means on the holder.

5. In a pneumatic hammer provided with a removable rivet-set, a set holder comprising similar hinged members tapered at the lower end, means on said holder for engaging the hammer and means surrounding and retaining said rivet-set, a sleeve threaded upwards over said holder and firmly clamping its tapered end, and a spring latch engaging said holder through said sleeve.

6. In a pneumatic hammer including a cylinder provided with a groove and a flanged rivet-set, a set holder comprising a pair of similar members hinged together longitudinally of the hammer, flange means on said holder for engaging in said groove and for engaging beneath the flange on said rivet-set, a sleeve threaded over said holder, and latch means carried by said sleeve and engaging in a notch in said holder through a slot in said sleeve.

In testimony whereof I have signed my name to this specification.

EDWARD L. BURTON.
